CLAIM

The ornamental design for a nose band harness as shown and described.

DESCRIPTION

The file of this patent contains at least one drawing/photograph executed in color. Copies of this patent with color drawing(s)/photograph(s) will be provided by the Office upon request and payment of the necessary fee.

1.1: Front view of a first embodiment;

1.2: Enlarged partial top view showing right side thereof;

1.3: Enlarged partial top view showing central portion thereof;

1.4: Top view thereof;

1.5: Rear view thereof;

2.1: Front view of a second embodiment;

2.2: Enlarged partial rear view showing central portion thereof;

2.3: bottom view thereof;

2.4: Enlarged partial front view showing a left side thereof;

2.5: Enlarged partial bottom view showing central portion thereof; and

2.6: Rear view thereof.

The broken lines illustrate portions of the nose band harness that form no part of the claimed design.
